CASING FOR A TAPE MEASURE

Robert A. Bennett, Shelton, Conn., assignor to
Waterbury Lock & Specialty Co., Milford, Conn.

Filed Sept. 20, 1971, Ser. No. 182,298

Term of patent 14 years

Int. Cl. D10—04

U.S. Cl. D52—1 R

FIG. 1

FIG. 2

FIG. 3

FIG. 4

FIG. 5

FIG. 6

FIG. 7

FIG. 1 is a front perspective view of a casing for a tape measure showing my new design;

FIG. 2 is a rear perspective view thereof;

FIG. 3 is a right side elevational view thereof;

FIG. 4 is a front elevational view thereof;

FIG. 5 is a rear elevational view thereof;

FIG. 6 is a top plan view thereof; and

FIG. 7 is a bottom plan view thereof.

I claim:

The ornamental design for a casing for a tape measure, substantially as shown and described.
